TYPEWRITING MACHINE

William F. Helmond, West Hartford, Conn., assignor to Underwood Elliott Fisher Company, New York, N. Y., a corporation of Delaware

Application December 14, 1933, Serial No. 702,301

14 Claims. (Cl. 197—102)

This invention relates to the keys of typewriting machines, and, for illustration, the invention is shown embodied in a well-known type of key, provided with a socket which fits upon the stem of a type-operating lever.

In a typewriter key, the character-bearing disk is usually capped by a glass disk. The hardness of the glass prevents it from being scratched or marred, and hence glass keys are esteemed for use on trial machines, as they do not become injured. The character-disk and the glass disk have usually been placed in a metal cup, and held in place by an annular key-cap, the latter having an inturned flange to hold down the glass disk. These flanges have been punishing the fingers of the operators for over fifty years.

Flangeless keys have been introduced, which are molded all in one piece, and fastened directly upon the key-stem, but they have not tended to supplant the glass-disk keys. The molded key, being made of celluloid or other inflammable material, is apt to become ignited. Moreover, it is easily scratched or defaced, and is also liable to soften from heat and become misshapen.

The glass key tops or disks are usually cut roughly from sheet-glass, and subjected to finishing operations, and, besides the raised flanges, have the further objection of being flat, and therefore not fitted to the finger of the operator.

It is one of the objects of the present invention to produce a typewriter key which overcomes these common objections.

One of the features of the invention is a key-top in the form of a concaved glass disk which is adapted to the finger and is not objectionably flanged and is cheaply produced and readily secured in place.

In the upper face of the glass, the corner is ground away to form an annular depression, in which fits an inturned fastening flange of the annular metal key-cap; said flange being preferably flat and flush with the glass disk at its border. No raised portion is encountered by the operator's finger; there is a broad concaved bearing surface of glass, having a flat metal border of moderate width, thereby avoiding undue reduction in the diameter of the key-top exposed between the inner edges of the flange.

To secure this width of the glass top, it is made of the same diameter as the key-cup, and surrounds the same, the glass being bedded upon a concaved pressed cork bed, the latter having the form of a disk which fits within the key-cup. The border of the glass top overlies the brim of the key-cup. The glass top is held firmly upon

the key by the flanged annular cap, and the area of the character-bearing surface is much extended as compared with glass keys now in common use; while the width of the inturned flange of the cap may be reduced from common practice, and the same rendered inconspicuous.

In some keyboards, the entire diameter of every key may be somewhat reduced, thus enlarging the space or well down into which the operator must dip his finger; and the finger is therefore not liable to catch upon any adjoining key, at either front, back or one side or the other; which is a substantial advantage, especially where it is desired to operate the keyboard without sight of the keys.

The bed for the glass top is a gasket that is inexpensively cut out from a sheet of pressed cork or cork-compound, having uniform thickness. The bottom of the metal key-cup is dished or concaved, to correspond with the convex bottom of the glass top, which is of uniform thickness. Thus the dished glass is solidly supported, and danger of breakage is avoided. The cork gasket is preferably pressed into concaved form before being placed in the cup. The cork is somewhat yielding, thus tending to cushion the key-touch and minimize the fatigue of operating the typewriter. The cork recovers its normal height when the pressure is released.

In one form of the invention, the character may be printed upon the bottom of the glass lens. Said bottom may be frosted or otherwise prepared to take the ink with which the character is printed. When the character is printed upon the bottom of the glass, the light pressure between the frosted bottom of the glass and the top of the cork gasket will prevent the glass from becoming accidentally rotated. The same is true when a key-paper is used.

The key-paper may consist of a thin card, which, after printing the character thereon, may be pressed into concave form, to form the bed or the upper layer of the bed which supports the concaved clear key-glass.

The character may be printed directly upon the cork disk, and the latter may be stained or colored to harmonize with the color of the casing in which the typewriting-machine keys are used.

If a printed key-glass is employed, the pressed cork gasket may be stained or colored. This coloring of the cork will give a beautiful effect through either clear or frosted glass.

From a large clear-glass dish, of uniform thickness, and of the same concavity that is desired in the finished key, many key-glasses may be cut

or formed. The glass-key top can be produced from any portion of the dish, and will be found to have the desired concaved form. The key-glass is finished to proper size and given the border-groove in its top for receiving the fastening flange.

Other features and advantages will herein-after appear.

In the accompanying drawing,

10 Figure 1 is a sectional front elevation of a typewriter key embodying the present improvements in one form.

Figure 2 is a perspective of a key-glass having a frosted bottom upon which the character is printed.

15 Figure 3 is a perspective of a compressed cork bed for the glass.

Figure 4 is a perspective view of a concaved key-paper.

20 Figure 5 is a sectional elevation showing the invention in a different form from Figure 1.

Figure 6 is a plan of the key seen at Figure 1 or Figure 5.

25 Figure 7 is a sectional view illustrating a step in the dividing out of a key-glass from a complete blown-glass globe or bulb, the diamond being indicated as cutting the key-circle in the blown globe.

Figure 8 illustrates the manner of grinding the 30 border-recess or groove in the top of the key-glass by means of an abrasive.

Figure 9 shows the division of a blown-glass globe into segments, preparatory to dividing them up into key-glasses.

35 Figure 10 illustrates the dividing of a segment up into many key-glasses.

Figure 11 shows a cork gasket stained with the desired color, and having the key-character printed directly thereon.

40 Figure 12 represents the assembled key as being provided with the stained or imprinted cork gasket of Figure 11.

Upon a key-lever stem 10 is forced down a socket-portion 12, formed in the bottom of a key-cup 13. The latter has circular rim or sides 14, and its bottom is concaved, as in Figures 1, 5, and 12 to correspond with the curvature of the key-glass.

Within the cup is placed a bed 15 of pressed 50 cork-compound, whose bottom is of spherical curvature, fitting the bottom of the key-cup 13.

Upon the bed 15 is placed a transparent glass 55 16, with concave top as at 17, and with convex bottom as at 18, the glass being inexpensively made of uniform thickness in the manner described herein.

Upon the bottom of the glass may be printed a character 19. The bottom may be frosted as indicated at 20, prior to printing the character.

60 In the top of the glass is ground an annular recess 21, to receive a fastening flange 22, formed upon a metal annular cap 23, which is fastened down by inturned ears or clasps 24, that hold the glass and bed 15 down upon the concaved bottom 65 13 of the cup, and also preferably in contact with the top of the key-lever stem 10 at 25.

The glass 16 may be the same diameter as the cup 13, and overlie the brim of the cup as seen at Figures 1 and 5; thereby affording a maximum 70 diameter to the key-glass for visibility, and also favoring the use of a key of somewhat less diameter than the common key. The width of the flange 22 is very slight, affording a relief to the eye, and the character-surface of the key may be very broad.

Said flange 22 may be flat and flush with the top of the key-glass at its border, so that a practically unbroken mainly concave surface extends the full width of the key.

At Figure 5, there is employed a disk 26 beneath the glass, having thereon a character as seen at Figure 4. This character-disk is made of card and printed, and then pressed into concave condition before being placed upon the cork bed 15. If desired, an adhesive may be employed as seen at 10 27, to hold the character-disk and cork bed together; and the glass is held down with such pressure as to prevent the character-disk from being accidentally rotated, this steadiness being due to the friction of the cork bed upon the bottom of the cup. When the character-disk is employed, the character is not printed upon the bottom of the key-glass, and the frosting may also be omitted.

The described glass-key tops may be made by 20 blowing a glass globe or bubble 28 of the desired wall-thickness, and having a concavity of the dimension desired for the key-top. The diameter of the blown-glass globe may be say three inches or a little less.

25 The cooled globe may be divided into major segments if desired. The major segments may have any desired contour. They may be dished or of circular form as seen at Figure 9.

Then each segment may be cut up into smaller 30 key-top-outlining segments to form many unfinished key-tops or glasses, as seen at Figure 10.

If desired, the key-glasses may be cut directly from the globe 28, without first dividing the latter into major segments 28a. This is illustrated at 35 Figure 7; the cutting being done by a rotary tool 29 having a diamond marker or cutter 30 herein. The glasses may be derived or separated from the bulb (or from a segment) by means similar to those employed in separating flat key-glasses 40 from sheet-glass. Then the recess or niche may be cut in the edge by the use of a hollow grinder 31, as seen at Figure 8, using an abrasive material.

There is thus produced an efficient, durable 45 key at low cost.

Variations may be resorted to within the scope of the invention and portions of the improvements may be used without others.

Having thus described my invention, I claim: 50

1. A typewriter-key having a glass top shaped with a brim and a crown which overtops said brim, said glass being curved bodily to make the crown concave and to make the glass of uniform thickness through the crown, a bed which is curved bodily to conform to said glass, said glass resting upon said bed, a cup having a concave bottom upon which said bodily curved bed rests, and an annular cap with an inturned flange bearing upon said brim of the glass top and being flush with the crown thereof, said annular cap being removably attached to said cup to hold the parts together.

2. A typewriter-key having an externally-concave glass top of practically uniform thickness, 65 a bed which is curved bodily to conform to said glass top, said glass top resting upon said bed, a cup having a concave bottom upon which said bodily-curved bed rests, and an annular cap with an inturned flange, the glass top being provided 70 with a brim and a crown which overtops said brim, said annular cap-flange bearing upon said brim and being flush with the crown thereof, said bed having a character inscribed thereon, the friction of the glass upon the character-bearing 75

- bed, effected by means of said annular cap, holding the character-bearing bed against the bottom of the key-cup, to locate the character-bearing bed rotatively.

5. 3. A typewriter-key having a cup, a yielding bed therein, a glass key-top of equal breadth with said cup and resting upon said bed, the bed being proportioned to space the glass key-top from the underlying rim of the cup, and an annular key-cap holding said glass key-top down upon said bed, the key-cap having an inturned glass-holding flange of a width about equal to the thickness of the wall of the cup, affording a broadened exposure of the surface of the key afforded by said glass key-top, said glass key-top having an annular border-recess into which said flange is sunken to be flush with the key-surface, said recess forming said glass with a brim upon which said flange bears and a crown which overtops said brim to be flush with said flange, a key-character marking being provided between said glass key-top and bed.

4. A typewriter-key having a cup, a glass key-top of equal breadth with said cup, said glass key-top being curved bodily to afford a concave top, a yielding bed in said cup upon which said glass key-top rests, said bed being proportioned to space the glass key-top from the underlying brim of the cup, and an annular key-cap holding said glass key-top down upon said bed, the key-cap having an inturned glass-holding flange of a width about equal to the thickness of the wall of the cup, affording a broadened exposure of the concave surface of the key afforded by said glass key-top, said glass key-top having an annular border-recess in which said flange is sunken to be flush with the key-surface, said recess forming said glass key-top with a brim upon which said flange bears and a crown which overtops said brim to be flush with said flange, a key-character marking being provided between said glass key-top and bed.

5. A typewriter-key having, in combination, an externally-concave glass top of practically uniform thickness, a gasket upon which said glass top rests, a cup in which said gasket is retained, said gasket being curved bodily and the bottom of the cup being concave to correspond with the curvature of said glass top, and an annular cap having an inturned flange for engaging over the border of said glass top, said annular cap being removably attached to said cup, to keep the parts together, the glass top being supported upon the gasket to overlie the rim of the cup and said flange being about equal in breadth to the wall of the cup, affording a broadened exposure of the surface of the key, said glass top being provided with a border-recess which shapes the glass top with a rim, upon which said cap-flange bears, and with a crown which is flush with said cap-flange.

6. A typewriter-key having an externally-concave glass top of practically uniform thickness, and an annular metal cap provided with an inturned flange, said glass top being provided with a border-recess which shapes said glass top with a brim, upon which said key-cap flange bears, and also shapes the glass top into a crown which is flush with said flange, said key-cap having means for interlocking with a support for the glass top to hold the parts together.

7. A typewriter-key having an externally-concave glass top of practically uniform thickness, a key-cup and a bed therein for supporting said

glass top, and an annular cap having an inturned glass-holding lip, said glass top being provided with a border-recess for said lip, said lip being thereby rendered flush with the glass top, said annular cap being removably attached to said cup for holding the parts together.

8. A typewriter-key having an externally-concave glass top of practically uniform thickness, a base by means of which the top is supported, and an annular cap attached to said base and having an inturned glass-holding flange, said glass top being provided with a border-recess forming a brim upon which said key-cap flange bears, and also forming the concave top into a crown substantially flush with said flange.

9. A typewriter-key having an externally-concave glass top of practically uniform thickness, a cup and a bed therein by means of which said glass top is supported, and an annular key-cap having an inturned flange which is sunken flush with said glass top, and is removably attached to said cup to keep the parts together, said glass top being furthermore provided with a border which shapes the glass with a brim upon which the key-cap flange bears, and which also shapes the concave top into a crown which is flush with said flange.

10. A curved-surface glass key-top of practically uniform thickness for a typewriter-key or the like, one side of said key-top being provided with a border-recess to form a brim, and a crown which overtops said brim, whereby said crown and a key-top-holding flange bearing on said brim may be flush at the periphery of the crown.

11. A typewriter key having a cup, a bed in the cup, a glass top resting on said bed, said glass top being formed with a brim and a crown that overtops said brim, and an annular cap with an inturned flange which bears upon said glass brim and is substantially flush with said crown, said annular cap being attached to said cup to hold the parts together.

12. A typewriter key having a cup, a yieldable bed in the cup, a glass top resting on said bed but overlying and spaced above the rim of the cup, said glass top being formed with a brim and a crown that overtops said brim, and an annular cap with an inturned flange which bears upon said glass brim and is substantially flush with said glass crown, said annular cap being attached to said cup to hold the parts together.

13. A typewriter key having a cup, a yieldable bed in the cup, a glass top resting on said bed, said glass top being formed with a brim and a crown that overtops said brim, means for preventing relative rotation between the glass top and the yieldable bed, and an annular cap with an inturned flange which bears upon said glass brim and is substantially flush with said glass crown, said annular cap being attached to said cup to hold the parts together.

14. A typewriter key having a cup, a yieldable bed in the cup comprising a cork disk, a glass top resting on said bed, said glass top being formed with a brim and a central crown which overtops said brim, the bottom of the glass top being frosted whereby relative rotation between the glass top and the cork bed is prevented, and an annular cap with an inturned flange which bears upon said glass brim and is substantially flush with said glass crown, said annular cap being attached to said cup to hold the parts together.

WILLIAM F. HELMOND.
